(No Model.)

M. F. FINNERTY,
CAR COUPLING.

No. 447,640.

Patented Mar. 3, 1891.

UNITED STATES PATENT OFFICE.

MICHAEL F. FINNERTY, OF BROOKLYN, NEW YORK, ASSIGNOR OF ONE-HALF TO GEORGE DITTRICH, OF SAME PLACE.

CAR-COUPING.

SPECIFICATION forming part of Letters Patent No. 447,640, dated March 3, 1891.

Application filed October 10, 1890. Serial No. 367,669. (No model.)

To all whom it may concern:

Be it known that I, MICHAEL F. FINNERTY, of Brooklyn, in the county of Kings and State of New York, have invented a new and Improved Coupling, of which the following is a full, clear, and exact description.

The object of the invention is to provide a new and improved coupling, which is simple and durable in construction, very effective, and automatic in operation, and specially designed for coupling cars together or ferry-boats to their slips, &c.

The invention consists of a transverse bar adapted to slide vertically in the draw-head and provided with a pin projecting at right angles to the said bar, and a coupling-link adapted to be engaged by the said bar and pin.

The invention also consists in certain parts and details and combinations of the same, as will be described hereinafter, and then pointed out in the claims.

Reference is to be had to the accompanying drawings, forming a part of this specification, in which similar letters of reference indicate corresponding parts in all the figures.

Figure 1 is a plan view of the improvement with parts broken out. Fig. 2 is a sectional side elevation of the same on the line *x* *x* of Fig. 1. Fig. 3 is a front view of the same with parts broken out and parts in section. Fig. 4 is a side elevation of a modified form of coupling-link, and Fig. 5 is a plan view of another improved form of coupling-link.

The improved coupling is provided with a draw-head A, having in its front end two compartments B and C, one located above the other and both adapted to receive the coupling-link D. In the upper part of the draw-head A is fitted to slide vertically a transverse bar E, extending into the upper compartment C, and from the said bar extends downward, at or near its middle, a pin G, passing through the partition between the two compartments and into and through the lower compartment B. The ends of the transverse bar E are provided with downwardly-extending arms E', fitted to slide vertically in suitable guideways F arranged on the sides of the draw-head A.

The coupling-link D previously mentioned is provided with a link proper D', adapted to pass into the lower compartment B to be en-

gaged at one end by the pin G. From the middle of this link proper D' extends upwardly a partition D², which supports a horizontally-extending bar D³, arranged parallel with the link proper D', and adapted to pass into the upper compartment C. The ends of the bar D³ are forked, as is plainly illustrated in Fig. 1, the prongs of each fork being provided with upwardly-extending hooks D⁴, adapted to travel under the rounded-off bottom of the transverse bar E, so as to raise the latter and pass to the rear thereof, in order to be engaged thereby when the said bar E has dropped. When the link D passes at one end into the draw-head A, the respective hooks E⁴ cause an upward sliding of the transverse bar E, so that the lower end of the pin G is raised to the top of the compartment B to permit the link proper D' to fully enter the compartment B. When the hooks D⁴ have passed to the rear of the bar E, the latter drops, then the pin G slides downward with the bar E and engages the respective end of the link proper D'. Then the link D is engaged simultaneously by both the transverse bar E and the pin G.

From the arms E' of the bar E extend outward pins E², adapted to be engaged by the side arms H' of a lever H, fulcrumed on the draw-head and provided with a crank-arm H², connected by a rope or chain I with an arm J', secured on a shaft J, extending transversely and mounted to turn in suitable bearings either on the draw-head A, as shown in the drawings, or at the end of the car. The outer ends of the shaft J extend to the sides of the car, and are provided with arms J² for manipulating the shaft J, in order to raise the bar E and its pin G without the operator stepping between the cars. If desired, the shaft J is manipulated from the top of the car by connecting its arm J' with a rope or link J³ extending through the top of the car. When the shaft J is turned, the arm J' pulls on the link I, so that the lever H is actuated and its side arms H' swing upward, thus pressing against the pins E², thereby raising the arms E' and supporting the bar E and the pin G. The top of the compartment is formed by a lid K, hinged at its rear end to the draw-head A, and serving to exclude dust, rain, &c.,

from the coupling. The upward movement of the bar E and its pin G is limited by the pins E' striking cross-bars F' arranged on the outside of the guide-ways F.

5 When it is desired to couple with an ordinary link only, the bar E is raised, as previously described, so that the pin G slides into its uppermost position, and the ordinary link is introduced into the compartment B, after 10 which the link is dropped and the cars are coupled.

Instead of the coupling-link shown in Figs. 1 and 2, a link as illustrated in Fig. 4 may be employed, the link proper D' and the partition D² being omitted, and only the bar D³ with its forked ends and hooks D⁴ is used. The hook ends pass into the upper compartment C, raise the bar E, and engage the latter, as previously described.

15 20 If it is desired to use the device for coupling a ferry-boat to a slip, then the link, as illustrated in Fig. 5, is used, having one forked end D³, with hooks D⁴, and pivoted at its other end at D⁵ on a pin L, held in a casing N, adapted to be secured to the ferry-boat and arranged to permit the link D to fall into the casing when not in use, as is illustrated in dotted lines in the said figure. The draw-head in this casing is arranged on the slip, 25 and when the boat enters and the link is in the position shown in Fig. 5 then the hooks D⁴ pass into the compartment C, raise the bar E and engage the latter, as above mentioned, so that the ferry-boat is coupled to the 30 slip.

35 Having thus described my invention, what I claim as new, and desire to secure by Letters Patent, is—

40 1. In a coupling, the combination, with a transverse bar mounted to slide vertically in the draw-head and provided with a downwardly-extending pin, of a coupling-link provided with a link proper adapted to be engaged by the said pin and with a forked bar 45 having hooks at its ends adapted to engage

the said bar, substantially as shown and described.

2. In a coupling, the combination, with a draw-head provided with an upper and a lower compartment, of a bar extending transversely in the said upper compartment and fitted to slide vertically in the said draw-head, a pin projecting downward from the said bar to pass into the lower compartment, and a coupling-link adapted to be engaged by the said 50 bar and the said pin, substantially as shown and described.

3. In a coupling, the combination, with a draw-head provided with an upper and a lower compartment, of a bar extending transversely in the said upper compartment and fitted to slide vertically in the said draw-head, a pin projecting downward from the said bar to pass into the lower compartment, a coupling-link provided with a link proper 60 adapted to enter the lower compartment to be engaged by the said pin, and a bar held above the said link proper and provided with forked ends and hooks adapted to engage the said transverse bar, substantially as shown 70 and described.

4. In a coupling, the combination, with a draw-head provided with an upper and a lower compartment, of a bar extending transversely in the said upper compartment and 75 fitted to slide vertically in the said draw-head, a pin projecting downward from the said bar to pass into the lower compartment, a coupling-link provided with a link proper adapted to enter the lower compartment to be engaged by the said pin, a bar held above the said link proper and provided with forked ends and hooks adapted to engage the said transverse bar, and means, substantially as described, for raising the said bar, as set 80 forth.

MICHAEL F. FINNERTY.
